US0D1112383S

(12) **United States Design Patent** (10) Patent No.: **US D1,112,383 S**
(Xu et al.) (45) Date of Patent: ** Feb. 10, 2026

(54) **COMBINED POLISHING AND GRINDING DEVICE**

(71) Applicant: **Hangzhou Sizone Electronic Technology Inc.**, Hangzhou (CN)

(72) Inventors: **Xiaoyu Xu**, Zhejiang (CN); **Zheng Xu**, Zhejiang (CN)

(73) Assignee: **Hangzhou Sizone Electronic Technology Inc.**, Hangzhou (CN)

(**) Term: **15 Years**

(21) Appl. No.: **35/522,630**

(22) Filed: **Aug. 29, 2024**

(80) **Hague Agreement Data**

Int. Filing Date: **Aug. 29, 2024**

Int. Reg. No.: **DM/240665**

Int. Reg. Date: **Aug. 29, 2024**

Int. Reg. Pub. Date: **Oct. 11, 2024**

(30) **Foreign Application Priority Data**

Jul. 30, 2024 (CN) 202430477132.8

CLAIM

The ornamental design for a combined polishing and grinding device as shown and described.

DESCRIPTION

The patent or application file contains at least one drawing executed in color. Copies of this patent or patent application publication with color drawing(s) will be provided by the Office upon request and payment of the necessary fee.

2. Combined polishing and grinding device

2.1: Front

2.2: Back

2.3: Left

2.4: Right

2.5: Top

2.6: Perspective

2.7: Perspective

2.8: Perspective

This design is used for polishing and grinding of wafer substrate.

The lightened areas with a broken-line boundary depict portions of the combined polishing and grinding device that form no part of the claimed design.

1 Claim, 8 Drawing Sheets
(8 of 8 Drawing Sheet(s) Filed in Color)
